(57) **CLAIM**

The ornamental design for a microwave baking device, as shown and described.

DESCRIPTION

This application is related to co-pending Ser. No. 15/967, 725, filed May 1, 2018, which is incorporated herein by reference.

FIG. 1 is a top, front and left side isometric view of a microwave baking device showing our new design;

FIG. 2 is a bottom, left and rear isometric view thereof;

FIG. 3 is a top plan view thereof;

FIG. 4 is a bottom plan view thereof;

FIG. 5 is a front elevation view, the rear elevation being identical thereto;

FIG. 6 is a right side elevation view, the left side being identical thereto;

FIG. 7 is a top, front and left side exploded view of the microwave baking device of FIG. 1; and,

FIG. 8 is a bottom, rear and left side exploded view thereof.
